UNITED STATES PATENT OFFICE.

ALBERT SVENSON, OF ENGLEWOOD, NEW JERSEY.

COMB-CLEANER.

1,222,484.

Specification of Letters Patent.

Patented Apr. 10, 1917.

Application filed June 16, 1916. Serial No. 104,049.

To all whom it may concern:

Be it known that I, ALBERT SVENSON, a subject of the King of Sweden, residing at Englewood, in the county of Bergen and 5 State of New Jersey, have invented new and useful Improvements in Comb-Cleaners, of which the following is a specification.

This invention relates to comb cleaners and it consists in the novel features herein- 10 after described and claimed.

An object of the invention is to provide a device of the character indicated which may be readily used for removing the oily matter from between the teeth of a comb whereby 15 the comb may be maintained in a clean condition by subjecting it to the action of the cleaner at intervals.

With the above stated object in view the cleaner comprises a frame adapted to be applied to a shelf or other suitable support and having spaced brushes journaled thereon. Wires are suitably supported and disposed transversely with relation to the 20 brushes and the spaces between the brushes. The said wires are spaced from each other and ample room is provided below the lowermost brush to permit the presence of a tray 25 below the brushes, the said tray being adapted to catch the material which is removed 30 from the comb during the cleaning operation.

In the accompanying drawings:—

The Figure 1 is a perspective view of the 35 comb cleaner.

Fig. 2 is a detailed sectional view of parts of the same.

As illustrated in the accompanying drawings the comb cleaner comprises a frame 1 which is substantially of rectangular con- 40 figuration and which is provided with feet 2 adapted to be secured by means of screws or other suitable securing devices to a shelf or other support. A frame 1' is located within the frame 1. Cylindrical brushes 3 are journaled upon the said frames and the 45 said brushes are spaced from each other. The shafts of the brushes pass through the sides of the frames 1 and 1' and serves as

supports for the frame 1'. The brushes are also in parallel relation with respect to each other. Wires 4 are connected with the upper and lower side portions of the frame 1' and the said wires are disposed transversely across the brushes 3 and transversely across the spaces between the said brushes. The 55 lower side of the frame 1' is elevated above the support upon which the cleaner rests and a tray 5 is positioned below the frame 1' and under the said brushes.

When the cleaner is in use the teeth of the 60 comb are inserted through the spaces between the wires 4 and then the comb is moved vertically along the said wires. As the comb moves along the said wires they cut and loosen the material which is between the 65 teeth of the comb and when the teeth come in contact with the brushes 3 the bristles of the brushes encounter the loosened material and knock or withdraw the said material from between the teeth of the comb. Inasmuch as the brushes are free to rotate they 70 may turn as they are encountered by the comb and thus the material which is removed by the bristles of the brush from between the teeth may eventually fall from 75 the teeth into the tray 5.

From the foregoing description taken in conjunction with the accompanying drawing it will be seen that a comb cleaner of simple structure is provided and that the 80 same may be readily used for efficiently removing the foreign matter or material from between the teeth of a comb and thus maintain the comb in a proper clean condition.

Having described the invention what is 85 claimed is:—

A comb cleaner comprising an outer frame, spaced brushes having shafts journaled therein, an inner frame supported by the shafts of the brushes, and wires mounted on 90 the inner frame and disposed transversely across the brushes and the space between the same.

In testimony whereof I affix my signature.

ALBERT SVENSON.
